HELICOPTER

Drago K. Jovanovich, 357 24th St., Santa Monica, Calif.

Filed Apr. 15, 1960, Ser. No. 60,212

Term of patent 14 years

(Cl. D71—1)

FIG. 1 is a perspective view of a helicopter embodying my new design;

FIG. 2 is a side elevational view of the FIG. 1 helicopter; and

FIG. 3 is a top plan view of the FIG. 1 helicopter.

The dominant features of the design reside in the portions shown in full lines.

I claim:

The ornamental design for a helicopter, substantially as shown and described.
